Primary Examiner — Rosemary K Tarcza(74) *Attorney, Agent, or Firm* — Banner & Witcoff, Ltd.(57) **CLAIM**

The ornamental design for a portable power station as shown and described.

DESCRIPTION

FIG. 1 is a rear top perspective view of a portable power station showing my new design;

FIG. 2 is a front top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and

FIG. 9 is a rear top perspective view of the portable power station showing the handle in an alternate position;

FIG. 10 is a front top perspective view thereof;

FIG. 11 is a rear top perspective view of the portable power station shown with the handle in a second alternate position; and,

FIG. 12 is a front top perspective view thereof.

The broken lines depict portions of the portable power station that form no part of the claimed design.

1 Claim, 12 Drawing Sheets(56)
